Attorney

UNITED STATES PATENT OFFICE.

AUGUSTA P. COOLBROTH, OF PORTLAND, MAINE.

VEIL.

1,256,205.

Specification of Letters Patent. Patented Feb. 12, 1918.

Application filed October 14, 1916. Serial No. 125,720.

To all whom it may concern:

Be it known that I, AUGUSTA P. COOLBROTH, a citizen of the United States, residing at Portland, county of Cumberland, 5 State of Maine, have invented certain new and useful Improvements in Veils, of which the following is a specification.

This invention relates to veils, and particularly to an adjusted net fall veil.

10 The object of my invention is to provide a neat and attractive veil which will permit the wearer free vision and proper respiration while effectively retaining the hat in place, if a hat be worn, as well as properly 15 confining the hair and preventing the entrance of wind and dust into the veil at the neck and side. This object is secured by the veil of the present invention. In carrying out my invention I make the main portion 20 of the veil of woven material having a relatively fine mesh and incorporate therein a section of woven material of relatively open mesh. This section is completely surrounded by the main portion of the veil and 25 constitutes a sight section adapted to be disposed over the face of the wearer in the use of the veil. In addition, the veil is provided with means for quickly and comfortably adjusting it to the hat or head and for 30 conveniently securing it in adjusted position.

The construction and manner of use of my veil is fully disclosed in the specification which follows. In the drawings accompanying that specification I have shown a form of veil which has been found satisfactory in use and inexpensive of manufacture. Throughout this specification and drawings like reference characters are correspondingly applied and in the drawing.

Figures 1 and 2 are front and side views illustrating the manner of use of a veil made in accordance with my invention.

Fig. 3 is a plan view of the veil in blank 45 form, and

Fig. 4 is a general view of the veil removed and as seen from the rear.

In carrying out my invention I provide a length of woven material 1 of relatively 50 fine mesh into which substantially centrally thereof so as to be completely surrounded thereby, is secured in any desired manner, as by stitching, a sight section 2 of woven material of relatively coarse mesh. Stitched to 55 the blank 1 at its top edge, considering the blank as it appears in Fig. 3, is a tape 3.

The opposite ends of this tape are provided with interengaging means, as the ball and socket clasp 4, and when secured produces a fullness, indicated generally by the numeral 60 5, in that portion of the blank which is disposed over the crown of the hat in the use of the veil. This yieldingly gathered section 5 enables the veil to be fitted to hats of various sizes.

65 The opposite edge of the veil is provided with an elastic 6 which is run through between ribbons or the like 7 stitched to said edge and adapted to be passed under the chin and around the neck of the wearer and 70 secured in the back by knotting, or by a hook and eye or ball and socket fastener. This enables the lower edge of the veil to be snugly adjusted at the neck of the wearer. The fulness, indicated generally by the numeral 75 8, produced by the elastic 6 in the lower edge of the blank is adapted to be disposed below the mouth and over the chin of the wearer, and serves to prevent the entrance of wind and dust.

80 The free ends or side portions of the blank 1, indicated generally by the numeral 9, are adapted to be drawn over the ears and cheeks of the wearer, crossed at the back of the neck, and knotted below the chin, 85 these ends extending downwardly and being pinned to the coat or allowed to hang freely, as desired. With the veil thus adjusted the section 2 of open mesh is disposed over the face of the wearer, thus permitting practically unobstructed vision and proper respiration.

90 Various modifications in the form of this invention may be resorted to if within the limits of the appended claims.

95 What I therefore claim and desire to secure by Letters Patent is:

1. A veil consisting of a blank of woven material having a sight section incorporated therein and spaced from the longitudinal 100 edges of the blank, an elastic gathering device secured at one longitudinal edge of the blank and provided with inter-engageable elements at its free ends and adapted when said elements are engaged to produce a fullness in that portion of the blank separating said device from the adjacent edge of the sight section and which portion in the use of the veil lies over the forehead of the wearer, and an elastic gathering device secured at the opposite longitudinal edge of 105 the blank and adapted to produce a fullness 111

in that portion of the blank separating said device from the adjacent edge of the sight section and which portion in the use of the veil constitutes a closure disposed about the 5 chin and neck of the wearer.

2. A veil consisting of a blank of woven material having a sight section incorporated therein and spaced from the longitudinal edges of the blank, an elastic gathering device of less length than the blank secured at one longitudinal edge of the blank and provided with inter-engageable elements at its free ends and adapted when said elements are engaged to produce a fullness in 10 that portion of the blank separating said device from the adjacent edge of the sight section and which portion in the use of the veil lies over the forehead of the wearer, and an elastic gathering device secured at 15 the opposite longitudinal edge of the blank and adapted to produce a fullness in that portion of the blank separating said device from the adjacent edge of the sight section and which portion in the use of the veil 20 constitutes a closure disposed about the chin and neck of the wearer.

3. A veil consisting of a blank of woven material having a sight section of woven material of different mesh incorporated 25 therein and spaced from the longitudinal edges of the blank, an elastic gathering device secured at one longitudinal edge of the blank and provided with inter-engageable elements at its free ends adapted when said 30 elements are engaged to produce a fullness in that portion of the blank separating said device from the adjacent edge of the sight section and which portion in the use of the veil lies over the forehead of the wearer, and 35 an elastic gathering device secured at the 40

opposite longitudinal edge of the blank and provided with covering elements extending beyond the ends of said device and constituting tie strings adapted to be tied under the chin of the wearer and adapted when 45 tied to produce a fullness in that portion of the blank separating said device from the adjacent edge of the sight section and which portion in the use of the veil constitutes a closure disposed about the chin and neck 50 of the wearer.

4. A veil consisting of a blank of woven material having a sight section of woven material of different mesh incorporated 55 therein and spaced from the longitudinal edges of the blank, an elastic gathering device secured at one longitudinal edge of the blank and adapted to produce a fullness in that portion of the blank separating said device from the adjacent edge of the sight 60 section and which portion in the use of the veil lies over the forehead of the wearer, and an elastic gathering device secured at the opposite longitudinal edge of the blank and provided with covering elements 65 extending beyond the ends of said device and constituting tie strings adapted to be tied under the chin of the wearer and adapted when tied to produce a fullness in that portion of the blank separating said device from the adjacent edge of the sight section and which portion in the use of the veil constitutes a closure disposed about the chin and neck of the wearer.

In testimony whereof I affix my signature 70 in presence of two witnesses.

AUGUSTA P. COOLBROTH.
